(57) CLAIM

I claim the toilet step for children, as shown and described.

DESCRIPTION

FIG. 1 is a front perspective view of the toilet step.

FIG. 2 is a rear perspective view of the toilet step.

FIG. 3 is a top view of the toilet step; and,

FIG. 4 is a bottom perspective view of the toilet step.

The broken lines in the drawings are for illustrative purpose only and form no part of the claimed design. Additionally, any side view is omitted as being devoid of surface ornamentation.
